Patented Apr. 28, 1914.

UNITED STATES PATENT OFFICE.

FRANK WHITNEY DE WITT, OF JEROME, IDAHO, ASSIGNOR TO WESTERN NOVELTY AND MANUFACTURING COMPANY, A CORPORATION OF IDAHO.

SALES DEVICE.

1,095,088.

Specification of Letters Patent. Patented Apr. 28, 1914.

Application filed January 30, 1913. Serial No. 745,113.

To all whom it may concern:

Be it known that I, FRANK W. DE WITT, a citizen of the United States, and a resident of Jerome, in the county of Lincoln 5 and State of Idaho, have invented a new and Improved Sales Device, of which the following is a full, clear, and exact description.

The object of the invention is to provide a new and improved sales device for cigars 10 and other articles and more especially designed for use on the top of show cases or counters and arranged to display the cigars or other articles to the best advantage, to protect the articles from dust or from 15 unduly drying out, and to prevent unauthorized persons from surreptitiously abstracting the articles from the device.

In order to accomplish the desired result, use is made of a stand or support, a jar 20 hinged to the said stand to swing from normal upright position into a tilted position, a cover for the said jar, and manually-controlled means for lifting the cover off the jar and tilting the jar.

25 A practical embodiment of the invention is represented in the accompanying drawings forming a part of this specification, in which similar characters of reference indicate corresponding parts in all the views.

30 Figure 1 is a perspective view of the sales device; Fig. 2 is a sectional side elevation of the same and showing one of the jars in tilted position; and Fig. 3 is a rear end elevation of the same.

35 In dry climates it has been difficult to sell cigars and similar articles from the top of counters or show cases owing to the fact that the cigars dry out in a comparatively short time and thus lose most of their essential qualities. With my device presently to 40 be described in detail the cigars are properly displayed, are protected against dust and prevented from drying out, and the cigars cannot be removed from their containers without action on the part of the salesman.

45 The sales device is mounted on a suitably constructed casing or stand A adapted to rest with its bottom A' on the top of the counter, show case or similar support B, and 50 the stand A is detachably secured to the support B by the use of front and back cleats C, C' attached to the bottom A', of which the front cleat C engages the front edge of the support B while the rear cleat C' is

provided with a clamping screw C² adapted 55 to abut against the rear edge of the support B.

The stand or casing A is provided with a number of steps A², A³, A⁴ for supporting at their forward ends a corresponding number of jars or similar containers D, D', D², 60 preferably made of glass to permit of viewing the cigars or other articles contained in the jars. Each of the glass jars is provided with a metallic cup-shaped binding D³ at 65 the bottom, connected at the under side by a hinge E, E' or E² with the forward end of the corresponding step A², A³, A⁴ so that the rear portion of the corresponding jar D, D', D² is normally supported on the top of 70 the corresponding step A², A³ or A⁴, and each jar is adapted to swing forwardly into 75 an inclined position, as indicated in Fig. 2, relative to the jar D². The upper edge of each jar D, D', D² is provided with a binding D⁴, preferably made of felt or other suitable soft material, and the jars D, D', D² are closed while in normal upright position by covers F, F', F², of glass or other suitable material.

80 When it is desired to raise the covers F, F' and F² and tilt the jars D, D', D² into selling position, the following arrangement is made: The rear ends of the bottom bindings D³ of the jars D, D', D² are pivotally 85 connected by links G, G', G² with levers H, H', H² arranged within the casing A and fulcrumed therein, as plainly indicated in Fig. 2, the links G' extending through suitable openings formed in the steps A², A³ and 90 A⁴. The rear ends of the levers H, H' and H² extend through openings A⁵ in the back A⁶ of the casing A, and the rear terminals of the said levers are provided with fingerpieces H³ under the control of the salesman 95 to permit the latter to impart a swinging motion to any one of the levers whenever it is desired to lift a cover and impart a tilting motion to the corresponding jar D, D' or D².

The back A⁶ of the stand A is set somewhat 100 forward of the rear ends of the bottom A' and the top of the uppermost step A⁴ to accommodate the fingerpieces H³, thus avoiding undesirable projections at the rear end of the stand A. The rear ends of the levers 105 H, H', H² can be locked against movement by a locking plate I connected by hinges I' with the back A⁶, suitable locking means

being provided for locking the locking plate I in uppermost position at the time the said locking plate engages the under side of the rear ends of the levers H, H', H² to hold the same against movement. The lower ends of the links G, G', G² are connected with pull springs J, J', J² so as to normally hold the jars D, D', D² in upright position on the steps A², A³, A⁴. The covers F, F', F² 10 are mounted on the upper ends of vertically disposed rods K, K', K² mounted to slide up and down in suitable bearings L arranged on the steps A², A³ and A⁴, and the lower ends of the said rods K, K', K² are 15 pivotally connected with levers H, H', H² and are also connected with pull springs N, N', N² somewhat lighter than the corresponding springs J, J', J².

The operation is as follows: The jars 20 D, D' and D² filled with cigars or other articles are normally in upright position on the steps A², A³ and A⁴ of the stand or casing A. When a customer desires an article out of any one of the jars the 25 salesman presses the fingerpiece H³ of the corresponding lever H so that the desired jar is tilted forward into selling position and its cover F, F', F² is raised to permit the customer to remove one or more of the articles 30 contained in the tilted open jar. When this has been done the salesman releases the fingerpiece H³ to permit the springs J, N or J', N' or J², N² to return the corresponding jar to normal dormant position and to 35 lower the cover back to the top of the jar to close the same. During any time the sales device is not in use the salesman swings the locking plate I upward into locking position and locks the same to the stand or casing 40 A, so as to hold the levers H, H', H² against movement thereby preventing unauthorized persons from abstracting articles from the jars. By providing the upper ends of the glass jars D, D' and D² with bindings D⁴ 45 all undue noise is reduced to a minimum on closing the jars by the covers F, F', F². As the jars are preferably made of glass or other suitable transparent or translucent material the contents thereof can be readily 50 viewed by a customer to enable the latter to make the desired selection, after which the salesman manipulates the corresponding lever for consummating the sale.

The sales device shown and described is 55 very simple and durable in construction, and although I have shown the three jars arranged on the stand A, it is evident that one or more such jars may be mounted on a stand in the manner above described.

60 In case the cigars are put up in tin cans, such cans after the covers have been removed can be placed into the jars to permit of selling the cigars out of the original packages.

65 Having thus described my invention, I

claim as new and desire to secure by Letters Patent:

1. A sales device, comprising a support having a series of steps, jars, one for each step and each having the forward portion of its bottom projecting beyond the front edge of the corresponding step, hinges connecting the bottoms of the jars with the steps to allow of swinging the jars from normal upright position into a forwardly tilted position, independent manually-controlled actuating means connected with the said jars to move any one of the jars into tilted position independent of the other jars, and a spring connected with each of the said actuating means for returning the tilted jar to normal upright position on releasing the actuating means. 70

2. A sales device, comprising a support having a series of steps, jars, one for each step and each having the forward portion of its bottom projecting beyond the front edge of the corresponding step, hinges connecting the bottoms of the jars with the steps to allow of swinging the jars from normal upright position into a forwardly-tilted position, links connected with the said jars, springs pulling on the said links to normally hold the jars in upright position, and levers fulcrumed independent one of the other on the said stand and connected with the said links. 80

3. A sales device, comprising a support having a series of steps, jars, one for each step, and each having the forward portion of its bottom projecting beyond the front edge of the corresponding step, hinges connecting the bottoms of the jars with the steps to allow of swinging the jars from normal upright position into a forwardly tilted position, links connected with the said jars, springs pulling on the said links to normally hold the jars in upright position, levers fulcrumed independent one of the other on the said stand and connected with the said links, 100 covers for the said jars, and rods mounted to slide on the steps and carrying the said covers, the rods being connected with the said levers. 105

4. A sales device, comprising a support having a series of steps, jars, one for each step and each having the forward portion of its bottom projecting beyond the front edge of the corresponding step, hinges connecting the bottoms of the jars with the steps to allow of swinging the jars from normal upright position into a forwardly tilted position, links connected with the said jars, springs pulling on the said links to normally hold the jars in upright position, levers fulcrumed one independent of the other on the said stand and connected with the said links, covers for the said jars, rods mounted to slide on the steps and carrying the said covers, the rods being connected with the said 115 120 125 130

levers, and springs connected with the said rods to lower the covers on releasing the levers.

5. A sales device, comprising a support having a series of steps, jars, one for each step, and each having the forward portion of its bottom projecting beyond the front edge of the corresponding step, hinges connecting the bottoms of the jars with the steps to allow of swinging the jars from normal upright position into a forwardly tilted position, manually-controlled levers fulcrumed on the stand independent one of the other, links connecting the said levers with the corresponding jars, the rear ends of the levers being provided with fingerpieces arranged on the same level, and locking means on the stand adapted to engage the said lever to lock the same against movement.

10 to allow of swinging the jars from normal upright position into a forwardly tilted position, manually-controlled levers fulcrumed on the stand independent one of the other, and links connecting the said levers with the

15 corresponding jars, the rear ends of the levers being provided with fingerpieces arranged on the same level.

6. A sales device, comprising a support having a series of steps, jars, one for each step, and each having the forward portion

of its bottom projecting beyond the front edge of the corresponding step, hinges connecting the bottoms of the jars with the steps to allow of swinging the jars from normal upright position into a forwardly tilted position, manually-controlled levers fulcrumed on the stand independent one of the other, links connecting the said levers with the corresponding jars, the rear ends of the levers being provided with fingerpieces arranged on the same level, and locking means on the stand adapted to engage the said lever to lock the same against movement.

In testimony whereof I have signed my name to this specification in the presence of two subscribing witnesses.
